INKWELL

Alfredo Silveira Avila de Melo, Lisbon, Portugal

Application December 30, 1936, Serial No. 118,420
In Portugal September 2, 1936

5 Claims. (Cl. 120—61)

The present invention relates to containers for writing fluids or the like and particularly to containers of the type in which attempt is made to provide a body of writing fluid of constant depth for the purpose of insuring the immersion to the same extent of the point of a pen inserted into the container from time to time.

The container or, as more commonly expressed, the inkwell, which comprises subject matter of the present invention includes, in addition to the usual receptacle for writing fluid or the like, a float which normally rests upon the surface of the writing fluid, the float preferably having sufficient buoyancy to not only support its own weight but to also support the weight of a pen resting upon the same and the float likewise being so formed as to define a small reservoir or pocket for writing fluid, quite apart from the main body of writing fluid in the container, into which the pen may be dipped and in which it will always be submerged to the same extent, regardless of the volume or level of the liquid within the reservoir.

The novel inkwell may be designed and constructed for use with pens of various sizes and weights, but preferably is designed for use with a pen of definite size and weight, which pen is normally positioned with its point resting upon the float within the container but which may be readily withdrawn at any time for writing purposes.

The invention not only provides means for ensuring that the point of a pen inserted therein shall be immersed only to a predetermined constant depth, but so functions to render available for use practically every portion of the body of ink placed within the container, and this notwithstanding the fact that a very small volume of ink indeed may remain in the container after it has been in use some time without refilling, the action of the float being such as to force within the pen point receiving recess formed therein, and thus render available for use, the last few drops of writing fluid remaining in the container.

The container and float may be varied widely in design and appearance, and the invention is likewise not at all limited with respect to the type of pen which may be employed. Thus the pen may be of the fountain pen type or of the ordinary type without capacity for the storage of ink. The invention is, however, particularly suitable for use in conjunction with pens of the fountain type, the point of any such pen, when inserted within the container, resting upon the float in such position as to facilitate charging of

the pen while at the same time preventing too deep an immersion of the pen in the writing fluid.

One embodiment of the invention has been selected for disclosure by way of example, and such embodiment is illustrated in the accompanying drawing, in which

Figure 1 is an axial section through the container and the enclosed float, a pen being illustrated in the position which it occupies when being inserted;

Figure 2 is a similar view but showing the pen fully inserted and the float in lowermost position, with container practically empty of fluid;

Figure 3 is a section on line 3—3 of Figure 2;

Figure 4 is a top view of the container, the pen being omitted in both Figures 3 and 4; and

Figure 5 shows in vertical axial section the cap or closure of the inkwell.

The container, as has been previously pointed out, may be formed in various ways, but essentially comprises a tubular portion or barrel 10, a bottom 11, preferably slightly conical as shown, and a removable top 12 the lower face of which is also preferably slightly conical, to substantially the same degree as is the bottom. The top 12 is 25 provided with a central aperture 13 for the insertion of a pen, such as the pen indicated at 14, and encircling this aperture and projecting upwardly from the top 12 is a cylindrical extension 15 provided interiorly with pen guiding 30 ribs 16 and exteriorly with threads 17 for engagement with the interiorly threaded portion of the top or closure cap 18 which is normally positioned to close the container when not in use. Preferably the container barrel 10 is cylindrical. Within the container barrel is a float 20 which may be formed in various ways and of different materials but in any case is preferably so shaped in horizontal section as to be substantially coextensive in area with a horizontal section through the barrel 10, the diameter of the float being only slightly less than the inside diameter of the barrel, to prevent binding of the float within the barrel as it moves vertically with the rise and fall of the liquid level therein. The 35 cylindrical inner surface of the barrel 10 is provided with grooves 21, or the cylindrical outer surface of the float 20 may be provided with vertical grooves, these grooves providing relatively restricted fluid by-pass ducts around the 40 float 20.

Centrally the float is provided with an aperture or recess 22 which extends entirely through the same from top to bottom thereof and the axis of which is aligned with the axis of the pen guiding 55

portion 15 of the container. A pen inserted through the aperture 13 in the container top will be guided by ribs 16 so that its point will enter the recess 22 and the pen 14 illustrated in Figure 2 is shown in this position, with the annular lower end surface 24 of the barrel resting upon an annular shoulder 25 of the float, shoulder 25 encircling the axis of recess 22. Radial grooves 26 maintain the recess 22 in communication with the space 10 above the float, even when the pen is positioned as shown.

The upper portion of recess 22 is generally cylindrical, as shown, and the lower portion is generally conical, terminating in a relatively restricted port 27 formed in the lower wall or bottom of the float. In vertical transverse section therefore the recess 22 corresponds substantially to the general shape of the pen point 28, sufficient clearance being provided between the edges of the pen point and the inner surfaces of the walls of recess 22 to ensure that the pen point, when at any time inserted, will not contact with the walls of the recess into which it extends, and quite regardless of the angular relative relationship of the pen and float at the time of insertion. The pen point 28 is likewise slightly shorter than recess 22 so that notwithstanding the fact that the float 20 may move downwardly as the ink level falls, to finally come to rest upon the bottom 30 of the container, the tip of the pen point cannot at any time strike the container bottom and thereby be injured, the lower end 24 of the pen barrel coming to rest upon the shoulder 25 before the tip of point 28 reaches the lower end of recess 35 22.

The container may be of course filled with ink until the upper surface of the float is in contact with the lower surface of the removable top 12. Assuming the ink level to be indicated by the dot 40 and dash line 30, the float 20 will occupy some such position as indicated by the dotted lines 31, when the pen is at rest upon and is being supported by the float. Falling of the ink level has no effect upon the extent of immersion of the float 45 until the float comes to rest upon the bottom of the container. At all times prior to contact of the float with the bottom 11 of the container, and when the pen is positioned upon the float, the upper surface of the relatively small body of 50 ink within the recess 22 will be well up toward the top of this recess, for instance at the level indicated by the dotted line 33 in Figure 2. Even when the float 20 comes to rest upon bottom 11 as shown in this figure, the level of the ink in recess 22 will 55 at first be at the elevation indicated by the line 33, practically all of the ink in the container having been forced into recess 22 by the action of the float. Hence it is clear that the float functions as a piston, making available for use practically all 60 of the ink originally placed in the container, an important advantage of the invention. Likewise the rather closely fitting float 20 functions to pre-

vent the too rapid outflow of ink in the event that the container is overturned, it being possible for the ink to escape only around the float 20 or through the aperture 22 formed centrally of the float and this flow being at a relatively slow rate 5 owing to the fact that it is difficult for air to flow around the float into the space between the float and the bottom of the container.

The float 20 may be fabricated of metal or any material resistant to writing fluids or the like and the container itself may be conveniently formed of glass or composition. The entire container is inexpensive to fabricate and is economical in the use of ink when used, the body of ink within the container having but little surface at any time exposed to the air. When a pen such as indicated at 14 is normally left in the position shown, a very small evaporation can take place, the lower end of the pen practically sealing off the upper end of recess 22. By shaping the bottom of the 20 container as shown, and rendering the bottom of the float correspondingly conical, the last remaining drops of fluid will tend to drain toward the port 27 in float 20 so as to pass readily into recess 22 when the float comes to rest on bottom 11. 25

Having thus described the invention, what is claimed as new and desired to be secured by Letters Patent is:

1. A container for writing or like fluids comprising a tubular barrel and bottom, and a float in 30 said barrel, the bottom surface of the float being adapted to bear upon substantially the entire area of the bottom of the container when the container is substantially empty, and the float having a pen point receiving aperture therein opening to 35 the bottom of the float into which the last remaining fluid will be forced by the float when the float reaches its lowermost position.

2. The combination set forth in claim 1 in which the float approximates, in horizontal section, the shape of the inside of the container, and in which vertical grooves are formed in the container barrel for the purpose set forth. 40

3. A container for writing or like fluids comprising a tubular barrel and bottom, and a float in 45 said barrel, the bottom surface of said float being adapted to bear upon substantially the entire area of the bottom of the container when the container is substantially empty, said float having a pen point receiving aperture therein opening to the 50 bottom of the float, said aperture having a diameter insufficient to receive the barrel of a pen, and being longer than that portion of the pen point which projects from the barrel of the pen.

4. The combination defined in claim 3, said 55 tubular barrel having guide means at its top for removably supporting a pen with the axis thereof vertically disposed.

5. The combination defined in claim 3, said float being sufficiently buoyant to support the 60 weight of a pen.

ALFREDO SILVEIRA AVILA DE MELO.
